UNITED STATES PATENT OFFICE

101,599

DESIGN FOR A CIRCULATION HEATER

David J. Howard, Chicago, Ill., assignor to Quaker Manufacturing Company, Chicago, Ill., a corporation of Illinois

Application July 9, 1936, Serial No. 63,746

Term of patent 3½ years

To all whom it may concern:

Be it known that I, David J. Howard, a citizen of the United States, residing at Chicago, in the county of Cook and State of Illinois, have invented a new, original, and ornamental Design for a Circulation Heater, of which the following is a specification, reference being had to the accompanying drawing, forming part thereof.

Figure 1 is a front perspective view of a circulation heater showing my new design;

Figure 2 is a section on the line 2—2 of Figure 1; and

Figure 3 is a section on the line 3—3 of Figure 1. Figures 2 and 3 are views on an enlarged scale. The side of the heater not shown in Figure 1 is like the side shown at the right hand portion of Figure 1.

I claim:

The ornamental design for a circulation heater substantially as shown and described.

DAVID J. HOWARD.
